UNITED STATES PATENT OFFICE

ORVILLE M. DUNNING, OF STAMFORD, CONNECTICUT, ASSIGNOR TO ACOUSTIC PRODUCTS COMPANY, A CORPORATION OF DELAWARE

MAGNETIC PICKUP

Application filed July 14, 1928. Serial No. 292,766.

The invention relates to electric reproduction from phonograph records.

One object of the invention is to provide an improved phonographic pickup of the 5 electromagnetic type.

In electromagnetic pickup structures, wave motion becomes inevitable. It has been found that the armature and needle have a natural resonance and that at the frequency 10 where this resonance occurs it will be seen that the reproduction will suffer due to the resonance and vibration of the armature and stylus adding to the vibration in response to the sound groove. It has also been found 15 that at all frequencies above the resonant vibration frequency of the assembly that the stylus tracks poorly, resulting in lowered output voltage.

It has been one object of the present invention to so design the various parts that the resonant characteristic of the stylus and armature occurs at such a high frequency as to not effect the voltage wave generation in response to sound grooves of normal musical 20 frequencies. In apparatus of this type, it has been previously possible to design a pickup in which the armature and stylus resonant frequency peak occurs at approximately 2500 cycles. With my improved 25 structure, however, it is possible to provide a device in which the armature stylus resonance occurs at a considerably increased frequency, thereby increasing the range of distortionless voltage wave generation in response to the sound groove of a record.

Another object of my invention is to provide a device in which the power generated in response to a given movement of a stylus driven armature is considerably increased, 40 and the amplitude distortion of the voltage wave generated materially decreased. This is accomplished by the provision of an armature moving between four poles constituting a magnetic field. In the present device, it has been found possible to pivot the armature midway between two pairs of the poles of the field, whereas it has been previously found necessary to pivot the armature between the two lower poles of the field.

50 In the design of devices of this type in the

past it has been found impossible to accomplish this for several reasons. In the first place, it is very desirable to design the armature in such a way as to use the standard length needles now in use. Since these are 55 usually about five-eighths of an inch in length, this requirement means that the needle holding screw must be within one-half inch of the surface of the record. Now, in order that the large mass of the needle holding screw may have no effect on the resonance characteristics of the armature system, it is absolutely necessary that the screw be located in the center of rotation of the armature and as close to its center of gravity as possible. In addition to this requirement it is also necessary that the stylus extend at least one-quarter inch below the bottom surface 60 of the pickup in order that the pole pieces and their support may not strike the surface of the record. It is further necessary, if the resonance of the armature system is to occur at a high frequency, to make the armature one-half inch or less in length. These requirements make it necessary that if the 65 armature is to be pivoted midway between the two pairs of poles, then the pole pieces, one-half the coil, and one-half the armature and needle holding screw bearings must be included within a space of one-quarter inch 70 or less, which has heretofore been impossible. In my design these requirements are fulfilled 75 in the following manner:

The thickness of the pole piece and its support are reduced to a minimum possible to 80 carry the necessary flux; the coil used consists of a very small number of turns instead of the usual several thousand turns, and no coil form is used, the coil being wound directly on the steel of the armature without insulation further than that on the wire.

In the present invention, there is provided 85 a moving armature, which is centrally pivoted between two pairs of magnet poles and about which there is directly wound a coil of few turns. The mechanical structure of the armature and its mounting and stylus retaining screw, as previously referred to and as will hereinafter be described in detail, is 90 95 100

such that resonance of the armature with the needle occurs at a very high frequency.

It will be seen that a few turns in the armature coil results in low impedance. It is common knowledge that if the inductance is decreased and the resistance also decreased in such a system, the power available remains constant, while the voltage is decreased in the ratio of turns. However, since the impedance of the circuit is lowered, it is possible 10 to use a higher step up input transformer ratio so that the resulting voltage at the secondary of the input transformer is independent of the turns or voltage of the generator. With the low impedance of the present wind- 15 ings the generated voltage decreases. This, however, coupled with the low impedance gives a resultant of power available equal to the high impedance coils of many turns as previously used. The present low impedance 20 circuit may, therefore, be coupled with a transformer system of high ratio whereby the resultant voltage of the pickup and transformer system remains high.

With these and other objects in view, to be 25 more fully set forth hereinafter, the invention consists in the novel construction, combination of elements and arrangements of parts which will be exemplified in the construction herein described in the following 30 specification and illustrated in the accompanying drawings.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

The invention will first be described in connection with the accompanying drawings, 40 wherein similar reference characters are used to designate corresponding parts throughout the several views, and more specifically defined and indicated in the appended claims.

45 Attention is directed to the drawings in which:—

Fig. 1 is a front plan view with the cover removed of one form of my present invention;

50 Fig. 2 is an enlarged sectional view taken on lines 2—2 of Fig. 1;

Fig. 3 is an enlarged sectional view taken on lines 3—3 of Fig. 1;

55 Fig. 4 is an enlarged detail view of an armature and windings utilized in my invention.

The drawings, forming part of the present application, embody only one form of the present invention. It is to be understood 60 that the novel features of the present device may be readily incorporated in various structural modifications. Referring to the drawings, there is provided a phonographic pickup including a case 1, to which may be secured any suitable type of cover. It is not

deemed necessary in the present application to disclose or describe any specific type of cover or associated elements, which form no part of the present invention. Secured to the base 1, there is provided a pair of pole pieces 2 and 3, each of which are provided, as illustrated, with two bifurcated poles designated by numerals 4 and 5, respectively. For providing a permanently energized magnetic circuit between the pole pieces, there is provided a permanent horseshoe magnet 6 positioned on the upper surface and at the extremities of the pole pieces 2 and 3. The pole pieces 2 and 3 are permanently secured to the base 1 by non-magnetic screws 7, together with a non-magnetic member 8 secured to the back 1 provides a magnetically insulated casing for the horseshoe magnet and its pole pieces. 70 75 80

Between the pole pieces 2 and 3 an armature 9 is provided, which is formed as illustrated in Fig. 4, including an upper armature flux conveying surface 10 and a lower flux conveying surface 11. The armature between these flux conveying surfaces 10 and 11 is tubular. The internal cross-section of the tubular portion is preferably provided with straight sides, as illustrated, and is thus adapted to receive and securely hold a conventional phonograph stylus. The armature is also provided midway between the flux conveying surfaces and at right angles to the tubular portion and lying in the plane of the flux conveying surfaces with extending bearing pinions 12 and 13. The rearward extending pinion 13 is adapted to be received within an enlarged portion 14 of the brass insulating plate 8 of the back 1. The forwardly extending pinion 12 is adapted to be received in a brass bearing member 15 secured to the pole pieces by the screws 6. The forwardly extending bearing pinion 12 is tubular and internally threaded to provide for the reception of a stylus engaging knurled screw 16. Thus, it may be seen that the weight and natural resonance of the stylus securing screw by virtue of its mounting at the pivotal point of the armature will not affect the movement of the armature or the armature and stylus resonant frequency. 90 95 100 105 110

Between the flux conveying surfaces and the pivotal points of the armature, there is provided a small number of turns of fine wire. By means of the present construction, the turns of wire may be directly wound upon the armature itself, thus avoiding the necessity of heavy coil forms, which would materially alter and lower the resonance frequency of the armature and stylus assembly. 115 120

The present construction allows for the coils to be closely wound directly upon the armature, thus avoiding flux leakage and resulting in a high voltage output. It will also be seen that the provision of only a few turns of the armature coil results in low im- 125 130

pedance coils. In the form of the invention illustrated, there is provided approximately ninety turns of wire directly upon the armature resulting in impedance of the order of a few ohms at 1,000 cycles. This may be favorably compared with the extremely high impedance ranging in order of several thousand ohms found in a single winding type of electromagnetic pickup. It may be readily seen that the low impedance in the present structure makes possible the use of a several hundred to 1 step up transformer ratio as compared with the 3 to 1 transformer ratio required in a single winding type instrument.

In devices of the present character, the flexibility of the needle and armature assembly materially decreases the resonant frequency of the assembly, causing a peak to occur in the frequency characteristic of the pickup. By the present structure, the armature is maintained extremely short and the direct magnetic flux is not carried by the armature as a result of the position of opposite poles on the two sides as indicated in Fig. 1, whereby the armature carries only the residual or alternating flux, hence the armature may be extremely light. This saving of weight in the armature does not, however, result in a decrease of magnetic effect due to the motion of the armature. On the contrary, the present structure increases the effect of movement of the flux conveying surfaces of the armature in response to the sound groove by providing two variable reluctance circuits for the magnetic flux. The small size and weight of the armature, together with its reenforcing windings and the centrally positioned receiver for the stylus securing screw, results in a reasonably flat voltage output-frequency characteristic up to a high frequency. The flexibility and mass of this assembly controls the frequency of the resonant peak of the assembly. This may be seen when it is remembered that by provision of a perfectly rigid armature and needle assembly that the resonance period would occur at infinitely high frequency and that the resonance period becomes of lower frequency as the flexibility and mass of the assembly increase.

Thus, the invention provides for a high resonance frequency armature and needle assembly, and, at the same time, provides decreased amplitude distortion and increased efficiency by increasing the variable reluctance of a plurality of magnetic circuits. By the opposite relation of the poles, as indicated in the drawings, it will be seen that the voltage waves generated are in phase and thus aid to produce an extremely efficient electric magnetic pickup device.

In accordance with the provisions of the patent statute, I have described my invention, but I desire it understood that it is not confined to the particular form shown and

described, the same being merely illustrated, and that the invention can be carried out in other ways without departing from the spirit of my invention, and therefore, I claim broadly the right to employ all equivalent instrumentalities coming within the scope of the appended claims, and by means of which objects of my invention are attained and new results accomplished as it is obvious that the particular embodiments herein shown and described are only some of many that can be employed to attain these objects and accomplish these results.

Having now described my invention, what I claim and desire to secure by Letters Patent, is:

1. An electromagnetic pickup including a four pole magnet, an armature having a pair of reluctance varying members disposed in reluctance varying position between the poles and a low impedance circuit comprising a few turns of wire directly wound upon the armature intermediate the reluctance varying members thereof.

2. An electromagnetic pickup including a four pole magnet, an armature having a pair of reluctance varying members disposed in reluctance varying position between the poles and a low impedance circuit comprising a few turns of wire directly wound upon the armature intermediate the reluctance varying members thereof, and means to pivot the armature intermediate the pole pieces.

3. An electromagnetic pickup including a four pole magnet, an armature having a pair of reluctance varying members disposed in reluctance varying position between the poles and a low impedance circuit comprising a few turns of wire directly wound upon the armature intermediate the reluctance varying members thereof, and means to pivot the armature intermediate the pole pieces, said circuit including turns of wire on either side of the pivoting means.

4. An electromagnetic pickup including a four pole magnet, an armature having a pair of reluctance varying members disposed in reluctance varying position between the poles and a low impedance circuit comprising a few turns of wire directly wound upon the armature intermediate the reluctance varying members thereof, and means to pivot the armature intermediate the pole pieces, said circuit including turns of wire on either side of the pivoting means, said pivoting means being apertured to receive therethrough a stylus securing member.

Signed at Stamford, in the county of Fairfield and State of Connecticut, this 28th day of June, A. D. 1928.

ORVILLE M. DUNNING.
